ATTORNEY.

UNITED STATES PATENT OFFICE.

CHARLES F. HOWENSTEIN, OF FORT WAYNE, INDIANA.

MOP HEAD.

Application filed April 12, 1922. Serial No. 555,061.

To all whom it may concern:

Be it known that I, CHARLES F. HOWENSTEIN, a citizen of the United States, residing at Fort Wayne, in the county of Allen and State of Indiana, have invented new and useful Improvements in Mop Heads, of which the following is a specification.

The invention relates to mop heads, and its object is to provide a simple, substantial and economically built head in which the mop may be securely fastened in such manner that the mop is readily attached or detached and affords easy and thorough ringing of the mop. Another object is to so form the head that the mop is readily inserted in corners and other places ordinarily difficult to reach. Other objects will appear hereinafter.

In the accompanying drawings I illustrate one manner of practicing the invention, in which Figure 1 is an elevational view of the mop, head and handle assembled; Fig. 2 a plan view of the head; Fig. 3 an edge view of the same and Fig. 4 a vertical section of the head with the mop securing means unfastened and depending therefrom.

Referring to the drawings, 1 is the usual handle having its lower end adapted to be inserted into a sleeve or socket 2 formed on the upper side of the head 3 and secured therein by any suitable means, as screw or bolt 4. The head is somewhat flat, as shown, and is formed in the shape of a heart—that is, tapered toward its lower end.

35 A groove 5 is formed in the edge of the head and extends around the same on all sides except the top, and opening through the top as shown. Adjacent the upper end of the groove at one end of the head is mounted a screw or other suitable member 6 upon which is mounted a chain 7, by engaging a link thereof on the member 6. A lever 8 is secured to the opposite end of the chain or to a link at said end. Two pins 9 project from

45 opposite sides of the lever at its lower end and below the point of attachment of the lever to the chain. These pins are adapted to be engaged in the notches 10 formed in the top of the head at the upper end of the groove 5 so that when the lever is engaged in the notches the chain will depend in the groove from the lever just as it does from the screw member 6 on the opposite side of the head.

Above the attachment point of the chain 55 to the lever, the lever is extended upwardly and inwardly toward the handle and also

curved sufficiently to permit said portion of the lever to embrace the handle.

To insert a mop 11 the chain is passed through the same, where the mop is of the cotton cord type, or if rags or cloth is used the latter are merely laid on the chain. The chain with its burden is then drawn around the periphery of the head in such manner that the chain will carry the material into the groove 5. The pins 9 on the lever 8 are engaged in the notches 10 and the lever is then rocked towards and into contact with the handle. The point of attachment of the chain is now between the pivotal point of the lever and the stick and the pull of the chain is substantially straight down on the lever from the said point of attachment. Hence the lever is rigid against the stick and will not rock outwardly no matter how much draft is applied to the mop when ringing the same. Yet, by manually rocking the lever outwardly the mop is readily removed. The insertion and removal of the mop is therefore accomplished readily. There is no bunching of the mop material at the edge of the head, hence the mop may be wrung up to the head and all surplus water readily removed. The tapering shape of the head forms somewhat of a point at its lower end to which the mop conforms, hence it is easy to insert the mop into a corner and other ordinarily inaccessible places.

Any number of links may be left on the chain above its points of attachment to the head and to the lever. Preferably one or more links lie above the connection to the head so that where a larger mop is to be used the screw 6 may be removed and returned through one of the extra links above, thereby lengthening the chain. In a similar manner the chain may be shortened or any length of chain obtained according to the size of mop to be used.

100 What I claim is:

In a mop head, a substantially flat member having its side edges tapering toward the bottom to cause the outline of the member to be substantially heart-shaped and having in said edges a mop receiving groove which opens at its opposite ends at the top of the member, a pair of notches at the top of the head adjacent one end of the groove, a chain secured in the groove at the opposite end thereof and a lever secured to the opposite end of the chain and adapted to

be engaged in the notches and to be rocked therein toward the handle for locking the chain with a mop thereon in the groove, the connection of the chain to the lever being such that in the locking position of the lever the said point of connection of the chain to the lever lies in a plane between the vertical planes of the handle and the pivotal point of the lever.

In witness whereof I have hereunto subscribed my name this 13th day of April, 1922.

CHARLES F. HOWENSTEIN.
